UNITED STATES PATENT OFFICE

134,927

DESIGN FOR A MONUMENT

Albert H. Johnson, Wausau, Wis., assignor to Anderson Bros. & Johnson Co., Wausau, Wis., a corporation of Wisconsin

Application October 26, 1942, Serial No. 108,611

Term of patent 14 years

To all whom it may concern:

Be it known that I, Albert H. Johnson, a citizen of the United States, residing in Wausau, county of Marathon, and State of Wisconsin, have invented a new, original, and ornamental Design for a Monument, of which the following is a specification, reference being had to the accompanying drawing forming part thereof, and wherein the figure is a front perspective view of a monument showing my new design.

I claim:

The ornamental design for a monument, as shown.

ALBERT H. JOHNSON.
